UNITED STATES PATENT OFFICE.

EDGAR P. COOK, OF GRANVILLE, OHIO.

AIR-GUN.

1,116,675.

Specification of Letters Patent. Patented Nov. 10, 1914.

Application filed October 16, 1913. Serial No. 795,516.

To all whom it may concern:

Be it known that I, EDGAR P. COOK, a citizen of the United States, residing at Granville, in the county of Licking and State of Ohio, have invented new and useful Improvements in Air-Guns, of which the following is a specification, reference being had to the accompanying drawings.

This invention relates to ordnance apparatus and more particularly to that class known as air-guns, air-pistols or air-rifles.

The main object of this invention is to have a gun constructed, so that it may be sufficiently accurate and powerful to be used for general sporting and target purposes, without requiring the use of gun-powder or other explosives to give the missiles used the necessary velocity.

Another object of this invention is to have the gun constructed, so that it may be manipulated with ease and at the same time be provided with means for adjusting parts of the gun, whereby its sensitiveness of action may be varied to suit the conditions arising or the person using it.

A further object is to provide a gun which will be comparatively noiseless and smokeless.

Other objects of this invention will become apparent as it is more fully set forth.

The gun referred to in this application consists in general of a barrel arranged to receive the bullet or shot cartridge, and a casing properly attached to the barrel and provided with the general parts of the device.

The working parts consist of a movable chamber having an opening arranged to align with the bore of the barrel so that the blast of air forced through the chamber by a plunger provided therein, will force the bullet or shot-cartridge from the gun in the manner desired. A suitable power-spring, together with catches and trigger mechanism are provided for the proper working of the plunger, and toggle, rack and pinion or other means for the proper working of the movable chamber, as will be more fully described in a later part of the specification.

In the accompanying drawings which illustrate embodiments of this invention, Figure 1 represents a side elevation of a shoulder gun embodying this invention.

Fig. 2 represents a side elevation of a one hand gun embodying this invention. Fig.

3. is a detail in perspective of a traveling air-chamber used in the gun. Fig. 4. is a transverse section of the gun on the line 9—9 of Fig. 8. Fig. 5. is a detail of a safety device used in the gun. Fig. 6. is a detail of a catch or sear used in the gun. Fig. 7. is a longitudinal section through a preferred form of bullet, to be used in this gun. Fig. 8. is a longitudinal section through the gun shown in Fig. 1, showing the working parts on a slightly enlarged scale. Fig. 9. is a detail section showing the working parts in loading position, and the relative positions of the power arm and air-chamber to permit the bullet or cartridge to be placed in the bore of the gun. It also shows the manner in which the set-lock is operated. Fig. 10. is a detail section showing the bullet and working parts in shooting or cocked position. Fig. 11. is a portion of a gun, seen from beneath, a portion of the casing cut away and showing the rack and pinion device for operating mechanism.

Similar reference characters refer to similar parts throughout the drawings.

In the construction shown in the drawings, 1 represents the stock, shoulder or hand portion of the gun and may be of any conventional design, and 2 is the trigger guard or protector, and is suitably attached to the gun. The casing containing the main working parts of the device is designated by the numeral 3, and the barrel by 4. The casing 3 is in general, cylindrical, except at the portion 5, adjacent to the stock, where it is arranged for the trigger mechanism, and other parts working in connection therewith. The casing adjacent to the barrel 4, is provided with an opening 8, through which the bullet or cartridge may be placed into a recess 6, of the barrel, provided for the same. The bore of the barrel is indicated by the numeral 7.

An air chamber 9 is provided in the casing and is arranged to slide easily in it. Its front portion 10, is provided with a hole through which the air blast is directed to the recess 6, when the gun is fired. A plunger 11, having a stem 12, is disposed in the air chamber 9, and closely fits the same, so that there will be but a slight leakage of air, when it is forced into the chamber 9, by the coiled spring 13, at the instant of firing the gun.

The catches or sears 14, are fulcrumed on the pivot 16, on the casing 34, and are pro-

vided with hooked ends 17, which engage on lugs 18, on casing 32, a part of the plunger or piston. Portions 19 of the sear are extended toward the rest of trigger mechanism and are actuated by a spring 21. The trigger proper is represented by 22, the trigger spring by 41, the set-hammer by 43, and the spring which actuates the hammer by 44.

10 The set screw 20, and set-screw keeper-screw 42 are provided for the proper adjustment of the trigger 22.

Fastened to the portion 10, of the air chamber is a lug or projection 25, to which 15 the lever mechanism is attached. Of this lever mechanism, 26 is the draw-bar, 27 the lever proper, 29 a catch for holding lever in its horizontal position, and 28 the hand-hold on lever 27.

20 In Fig. 11 the lever mechanism and lug 25, are not used, but a rack and pinion mechanism substituted instead. The rack of cogs is represented at 46, on the air chamber 9, the cog-wheel for actuating same is 25 represented by 47, and the crank by 48. A joint 49, is provided in the crank so that said crank may be folded under the gun. In this figure as well as in others 45 represents a projection from the traveling air-chamber which actuates the set-hammer 43, 30 as is shown in Fig. 9.

Referring to Fig. 7 which shows a detail of a preferred form of bullet, 30 indicates the bullet proper, 31 the rear flange of bullet, intended to take the rifling and spin the bullet, 33 the front band of bullet, intended to merely ride on the rifling lands and guide the bullet.

The safety as shown in Fig. 5 is composed 40 of a shaft 37, a projection 38, for engagement with portion 24, of sear as shown in Fig. 6. No. 39 of safety is a knurled portion of same designed for the safety's easy operation. This safety is pivotally connected 45 to the frame of gun.

In operating the lever design gun, the operator first pulls down on the lever 27, till the working parts are in the position shown in Fig. 9. This compresses the main-spring till the lugs 18 are caught on catches 50 17, and the projection 45, sets the hammer 43, in its cocked position. While the mechanism is in this position the bullet or cartridge is inserted into the recess 6, through 55 the opening 8, of casing, after which the lever is brought back to its horizontal position and the gun is ready to shoot.

In the rack and pinion design, the crank is first loosened from a catch holding it 60 under the casing, then turned outward as

shown in Fig. 11. Then by so turning it as to run the rack of cogs, on air chamber, back toward breech of gun, the spring will be compressed and hammer set as in Fig. 9. After inserting bullet or cartridge 65 the process is reversed, which closes the action.

The improvement claimed over the Patent No. 1,045,373 issued to Edgar P. Cook, Nov. 26, 1912, is in the means, part 45, used to 70 operate a set-lock mechanism, and a rack and pinion method of operating the general mechanism.

Obviously while only two modifications of this device are shown in the drawings, 75 it is not desired to limit this application for patent to that particular construction or in any other way otherwise than limited by the prior art as many modifications of this invention may be made without departing 80 from the principles thereof and coming within the scope of the appended claims.

Having thus described the invention, I claim:

1. In a device of the class described the 85 combination of a gun-barrel arranged to receive bullets or cartridges, a casing for holding said barrel, a hollow air-chamber slidably arranged within said casing, a plunger within said air-chamber, a coil spring 90 for actuating said plunger, trigger means for controlling said plunger means, means for slidably operating said air-chamber and thereby the plunger means, a means attached to or a part of said air-chamber which said means shall be so arranged as to operate the hammer of a set-lock or knock-off system or trigger mechanism during the operation of manually cocking the gun.

2. In a device of the class described, a gun barrel, a casing for holding said barrel, a hollow air-chamber slidably arranged within said casing, a plunger within said air-chamber, a spring for actuating said plunger, trigger means for controlling 105 said plunger and spring, means for operating the slidably air-chamber, a means attached to or a part of the slidably operable means which first mentioned means shall be so arranged as to set the hammer of a set-lock or knock-off system of trigger mechanism.

In testimony whereof I hereunto affix my signature in the presence of two witnesses.

EDGAR P. COOK.
